UNITED STATES PATENT OFFICE.

WILLIAM H. PEARCE, OF PHILADELPHIA, PENNSYLVANIA.

GAS OR VAPOR STOVE.

1,144,722.

Specification of Letters Patent. Patented June 29, 1915.

Application filed March 16, 1914. Serial No. 824,888.

To all whom it may concern:

Be it known that I, WILLIAM H. PEARCE, a citizen of the United States, residing in the city and county of Philadelphia, State 5 of Pennsylvania, have invented a new and useful Gas or Vapor Stove, of which the following is a specification.

My invention consists of a novel gas or vapor stove and relates especially to a top 10 adapted to be assembled with stoves of different sizes.

It further consists of a novel top provided with a novel construction and arrangement of heat radiating ribs or flanges so that the 15 top surface of such top plate will be highly heated around the pot opening, and several different articles may thus be heated from a single burner.

It further consists of a novel construction 20 and arrangement of grate or intermediate member and a novel manner of assembling the same with respect to the pot hole, so that the pot or cooking utensil may be raised above the upper surface of the top plate to 25 permit the products of combustion to pass upwardly around the sides of the same so that the contents will be quickly heated or the intermediate supporting plate or member may be arranged so that the cooking 30 utensil will have its bottom flush with the upper surface of the top plate. It further consists of a novel construction of ribs or flanges which serve to stiffen the top and prevent warping or cracking thereof.

35 It further consists of other novel features of construction, all as will be hereinafter fully set forth.

For the purpose of illustrating my invention, I have shown in the accompanying 40 drawings one form thereof which is at present preferred by me, since the same will give in practice satisfactory and reliable results, although it is to be understood that the various instrumentalities of which my invention 45 consists can be variously arranged and organized and that my invention is not limited to the precise arrangement and organization of these instrumentalities as herein shown and described.

50 Figure 1 represents a perspective view of a portion of a gas or vapor stove embodying my invention. Fig. 2 represents, in detached

position, a top plan view of a grate or intermediate member employed. Fig. 3 represents a sectional elevation on line y—y of 55 Fig. 5. Fig. 4 represents a bottom plan view of the intermediate member or grate seen in Fig. 2. Fig. 5 represents a top plan view of a gas or vapor stove embodying my invention, showing a somewhat different type 60 from that seen in Fig. 1. Fig. 6 represents in perspective a fastening device employed. Fig. 7 represents a section on line x—x Fig. 2. Fig. 8 represents a sectional elevation of 65 a portion of a gas or vapor stove embodying my invention and showing the intermediate member or grate in different positions with respect thereto. Fig. 9 represents a sectional elevation of a portion of my device showing more clearly the manner of fastening the top 70 plate to the stove. Fig. 10 represents in detached position a perspective view of the underside of the top plate.

Similar numerals of reference indicate 75 corresponding parts in the figures.

Referring to the drawings, 1 designates a gas or vapor stove having a top 2 provided with the grating 3 which covers the burners 4 to which any desired type of fuel is conducted through the conduit 5, and the admission of fuel to each burner being controlled by a valve 6 while the admission of air thereto is controlled by the usual type of air regulating means 7.

In accordance with my present invention, 85 the grating 3 is replaced by a novel top or cover plate 8 the construction of which will now be explained. This top 8 is provided with port holes or openings 9 therein and a laterally extending flange 10 preferably extending beneath the bottom face of the plate, as will be best understood by reference to Fig. 10. This rib or flange 10 forms the bottom wall of the opening 9 and its thickness is such that it terminates beneath the 95 top surface of the top 8 so as to form a support for a cover plate 11, see Fig. 5, so that such cover plate will be flush with the top of the member 8. Each cover plate 11 may, if desired, be provided with a port hole or 100 opening which is adapted to receive a smaller cover plate 12. The annular rib or flange 10 is provided with apertures 13 therethrough which conform to the shape of lugs 14 of an

intermediate grate or member 15. In the present instance, I have shown for purposes of illustration three lugs 14 and three apertures or recesses 13 with which they coöperate but it will of course be understood that any desired number of the same may be employed. This intermediate member, in the present instance, comprises a disk of metal or other suitable material 16 to the underside of which the lugs 14 are secured and the top face of the disk 16 is provided with a desired number of ribs or flanges 17 which have been shown for purposes of illustration as being four in number and arranged radially on the disk and extend toward the center thereof so as to extend over the aperture or opening 18 which may be of any desired contour but which, in the present instance, is shown as having the curved walls 19 so that the greatest width of the disk is in proximity to the top ribs or flanges 17.

Secured to the bottom of the plate which comprises the top 8 and preferably integral therewith are a series of independent depending ribs or flanges 20, 21, 22, 23 and 24. The rib or flange 20 extends laterally and transversely of the top 8 in close proximity to a port hole 9 while the ribs or flanges 21 and 22 extend longitudinally in proximity to the same port hole 9 and are spaced from the rib or flange 20 so as to form the openings 25 and 26. The ribs or flanges 23 and 24 have one end, as 27 and 28, located outwardly of the flanges 21 and 22 and openings 29 and 30 respectively are formed between the adjacent ends of such flanges. The opposite ends of the ribs or flanges 23 and 24 converge toward each other and terminate in proximity to an adjacent port hole opening 9, preferably cast integral with the flange 10 thereon. One end of the top 8 is provided with a downwardly directed rib or flange 31 which forms a continuation of the downwardly directed side flanges 32 and 33 respectively. 34 and 35 designate curved ribs or flanges extending from the end 36 of the top 8 inwardly and outwardly toward the side flanges 32 and 33 respectively, and terminating as at 37 and 38 respectively.

In order to provide for the adjustment of the top with respect to various sized openings of different stoves after the top grating 3 has been removed, I provide the locking members 39 having a slot 40 therethrough through which extends the screw-bolts or other fastening devices 41 which latter also pass through the top plate 8, and are provided with nuts 42 which are prevented from rotation owing to the provision of a groove 43 in a face of the locking device 39. The forward end of such member 39 is downwardly deflected as at 44 to form a lug having its outer face preferably beveled or inclined, as at 45, so that it will engage the

wall 46 of the stove top 2 and the end thereof be seated on the laterally extending flange 47.

In some cases stoves of this character are provided with a flue 48, as seen in Fig. 5. 70 In order that the same top plate may be employed with a stove having a flue for carrying off the products of combustion, I provide at one end of the top 8 the transversely extending slots 49 which are centrally located between the ribs 34 and 35 and the transversely extending slots 50 on each side of such rib and which are weakened in proximity to such ribs, as indicated at 51, so that the corner next to the flue 48 may be readily 80 broken off by a hammer or other implement so that the parts will appear as seen in Fig. 5.

The operation of my novel invention and the manner of applying the interchangeable top to gas or vapor stoves now in use is as follows:—The top 8 is assembled with respect to the stove, as best seen in Figs. 1, 5, 8 and 9, so that the flanges 31, 32 and 33 rest on the top 2 and the fastening devices 90 39 are then moved outwardly into engagement with the downwardly inclined walls 46 of the top 2, whereupon the set screws 41 are tightened thus fixing the top 8 in assembled condition with respect to the top of the 95 stove. If it is desired, the pot or cooking utensil may be placed so as to rest on the flange 10 or on the top surface of the plate or member 8 and owing to the novel construction and arrangement of the ribs or 100 flanges on the under surface of the plate the top surface surrounding the pot opening will be highly heated. If it is desired to quickly heat the cooking utensil, the grate 15 is placed over a pot hole 9 so that the lugs 14 rest on the flange 10. This will allow the heat from the burner to escape around the pot or cooking utensil and after the cooking utensil is at a boiling point, the member 15 is turned until the lugs 14 register with and are received in the openings 110 13. The pot hole is now entirely covered and the heat is deflected under and around the top of the stove coming in contact with the depending flanges 20, 21, 22, 23 and 24, 115 so that the heat absorbed by said flanges is radiated to the upper surface of the top plate.

When the pot hole is covered, the products of combustion pass around the radiating ribs or flanges and toward the open end 36 of the top plate and, if the pot hole 9 adjacent said end is uncovered, a portion of the products of combustion are directed toward the central portion thereof. The flanges 34 and 35 also act as radiating ribs and serve to retard the passage of the products of combustion from beneath the top plate 8, and also to stiffen the top plate at such point.

While I have referred to the construction 130

surrounding the pot opening as consisting of flanges, it is to be understood that such term is to include ribs or other projections arranged as set forth and serving to radiate and distribute the heat to the upper face of the top plate.

I am aware that it has heretofore been proposed in the art to employ means to distribute the heat from one pot opening to another, such as for example in the patent to Dean *et al.* 792,502, and in many patents prior thereto but my invention is clearly differentiated from such devices since I employ on the under face of the top plate ribs, lugs, flanges or projections, the function of which is to collect and radiate the heat to the upper face of the top plate so that the surface surrounding the pot opening is highly heated and to the hereinbefore referred to prior constructions I make no claim.

I do not intend to limit myself to the particular construction of top plate or pot supporting member hereinbefore described, but reserve the right to make such changes, variations, modifications, etc., as come properly within the scope of the appended claims.

It will now be apparent that I have devised a novel and useful construction of a gas or vapor stove which embodies the features of advantage enumerated as desirable in the statement of the invention and the above description, and while I have, in the present instance, shown and described a preferred embodiment thereof which will be found in practice to give satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. A top plate for gas or vapor stoves comprising a metal plate provided with a plurality of pot openings and having at one end and two sides only marginal downwardly deflected portions, said plate having a series of independent depending flanges some of which extend substantially laterally and the others longitudinally upon opposite sides of one of said pot openings in close proximity thereto.

2. A top plate for gas or vapor stoves comprising a metal plate provided with a plurality of pot openings and having at one end and two sides only marginal downwardly deflected portions, said plate having a series of independent depending flanges some of which extend substantially laterally and the others longitudinally upon opposite sides of one of said pot openings in close proximity thereto and flanges between said opening and the adjacent opening.

3. A top plate for gas or vapor stoves comprising a metal plate provided with a plurality of pot openings and having at one end and two sides only marginal downwardly deflected portions, said plate having a series of independent depending flanges some of which extend substantially laterally and the others longitudinally upon opposite sides of one of said pot openings in close proximity thereto and flanges between said opening and the adjacent opening, the adjacent flanges being convergent.

4. A top plate for gas or vapor stoves comprising a metal plate provided with a plurality of pot openings and having at one end and two sides only marginal downwardly deflected portions, said plate having a series of independent depending flanges some of which extend substantially laterally and the others longitudinally upon opposite sides of one of said pot openings in close proximity thereto and flanges between said opening and the adjacent opening and curved ribs at the corners at one end of said plate.

5. A top plate for gas or vapor stoves having a pot hole with an inwardly laterally extending flange forming the bottom wall of said hole and having radial apertures and depending flanges integral with said flange and extended upon a plurality of sides of said hole, and a member having lugs conforming to said apertures and its top face provided with ribs radially extended, said member having an aperture with curved walls between said ribs with the greatest width of the plate in proximity to said ribs and the latter extended inward beyond the inner margin of the plate.

6. A top plate for gas or vapor stoves having a pot hole with an inwardly laterally extending flange forming the bottom wall of said hole and having radial apertures, and a member having lugs conforming to said apertures and its top face provided with ribs radially extended, said member having an aperture with curved walls between said ribs, with the greatest width of the plate in proximity to said ribs and the latter extended inward beyond the inner margin of the plate, the bottom of said top plate having independent depending flanges integral with the first-named flange and extending laterally transversely of the top plate and disposed in proximity to said pot hole.

7. A top plate for gas or vapor stoves having a pot hole with an inwardly laterally extending flange forming the bottom wall of said hole and having radial apertures, and a member having lugs conforming to said apertures and its top face provided with ribs radially extended, said member having an aperture with curved walls between said ribs, with the greatest width of the plate in

proximity to said ribs and the latter extended inward beyond the inner margin of the plate, the bottom of said top plate having independent depending flanges integral with the first-named flange and extending laterally transversely of the top plate and disposed in proximity to said pot hole and

with flanges extending from an adjacent pot hole toward the first-named flanges and diverging from each other.
